(57) **CLAIM**

The ornamental design for a nose hair trimmer, as shown and described.

DESCRIPTION

FIG. 1 is a front, right and top perspective view of a nose hair trimmer, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a first perspective view showing in state of use;

FIG. 10 is a second perspective view showing in a state of use;

FIG. 11 is a third perspective view showing in a state of use; and,

FIG. 12 is a fourth perspective view showing in a state of use.

The broken lines shown in FIGS. 9-11 illustrate the environment of the nose hair trimmer and form no part of the claimed design. The remaining broken lines illustrate portions of the nose hair trimmer and form no part of the claimed design.
